BAFFLE ELEMENT FOR A MATERIAL SPREADING DEVICE

Harlan J. Donelson, Jr., West Highway 330,
Marshalltown, Iowa 50158

Filed Oct. 2, 1968, Ser. No. 13,815

Term of patent 14 years

Int. Cl. D15—03

U.S. Cl. D40—1

Fig. 1

Fig. 2

Fig. 3

Fig. 4

FIG. 1 is a top perspective view of a baffle element for a material spreading device showing my new design;

FIG. 2 is a side elevational view as seen from the right-hand side of FIG. 1 and at an enlarged scale;

FIG. 3 is a top plan view thereof; and

FIG. 4 is a bottom plan view thereof.

I claim:

The ornamental design of a baffle element for a material spreading device, substantially as shown.
